METHOD FOR FASTENING WORKPIECES TO
METAL PLATES

Georg Karl Johan Broberg, Solna, Sweden, assignor to AB Svenska Fläktfabriken, Stockholm, Sweden

Application August 17, 1949, Serial No. 110,858

Claims priority, application Sweden
August 28, 1948

3 Claims. (Cl. 29—148)

1

This invention relates to a method for fastening an edge of a work-piece to the surface of a sheet metal plate or the like.

The object of the invention is to provide a simplified and cheap way of fastening an edge of a work piece to the surface of a sheet metal plate. According to hitherto known methods, welding or soldering has been utilized for such fastening operations, which has meant a complication of the manufacture, or the use of such complicated mechanical machining methods and fastening means that they have made the production more expensive.

The method according to the invention is, in the first place, characterized in that an edge of the work-piece is placed underneath and in contact with the underside of the metal plate to serve as a die, while a punch is forced through said metal plate from the upper surface thereof to simultaneously cut two spaced slots corresponding substantially to the width and contour of the underlying edge of said work-piece and to displace or depress the metal plate adjacent said slots, after which another punch deforms the material of the metal plate located between said slots and also deforms or upsets the underlying edge of the work-piece which serves as the die, so that said deformed or upset edge of the work-piece is interlocked between the displaced or depressed portions of said plate and the deformed material between said slots.

Other characteristic features of the method according to the invention are treated in connection with two embodiments thereof more specifically described in the following specification.

The invention is illustrated in two of its embodiments in the accompanying drawings wherein, for purposes of illustration, Figures 1-4 show different phases of the production of one embodiment and Figures 5-11 show different phases of the production in accordance with the other embodiment.

Figures 1-4 illustrate how the edge of a substantially plane metal plate is fastened to the surface of another plane metal plate, and Figures 5-11 illustrate how the end of one or more double bent metal plates are fastened to the surface of a plane metal plate or substantially plane metal plate, Figures 6, 9, and 11 being sectional views on the lines 6—6, 9—9, and 11—11 of Figures 7, 8, and 10, respectively.

In Figure 1, the original position is shown for fastening the edge of a plane metal plate 12 to the surface of a likewise plane metal plate 13. According to the invention metal plate 12 serves

2

as a die for the punch 14, when said punch is pressed down against the metal plate 13.

In Figure 2, the shape of the metal plate 13 is shown after the punch 14 has accomplished its cutting and depressing actions as determined by the form of the punch.

Figure 4 shows a horizontal view of Figure 2 after the punch 14 has been taken away. From Figures 2 and 4 it is evident that the punch 14, as indicated by the lines 15 and 16 in Figure 4, cuts a metal strip 18 out of the metal plate 13, which metal strip is united at both ends with metal plate 13. Simultaneously with the cutting action just referred to, the punch 14 displaces or depresses from the metal plate 13, two tongues 19 and 20. These tongues form an angle with each other as will be apparent from Figure 2. From the same figure it is further apparent that the free edges of tongues 19, 20 lie closely adjacent the work-piece 12 at opposite sides thereof. The free edges of the tongues 19, 20 do not make close contact with the opposite sides of work-piece 12, as there is, in reality, a little space between the free edges of these tongues and the sides of said work-piece, as best shown in Figure 2a. Complete contact between said free edges and the sides of said work-piece may be obtained, however, by supporting the tongues 19, 20 during a final punching operation with a support (not shown) so that the tongues, by deforming, are pressed into contact with the metal plate 12 as shown in Figure 2. This contact may, on the other hand, be obtained in connection with a second punching operation in which the punch 14 further bends down the tongues 19, 20 so that the down pressed tongues in Figure 2 form grips resembling thumb grips, the sides 21, 22 and 23, 24 of which are united with metal plate 13. The reference numerals 21, 22, 23, 24 may, however, also represent lines (Figure 4) along which the metal plate 12 has been cut by the punch 14. From Figure 2 it is evident that after this punching, a cavity 25 has been formed between the metal strip 18 and the upper surfaces of the tongues 19 and 20.

In Figure 3, showing a cross section of a fastening joint complete according to the embodiment described, the first punching operation has been followed by a second one with a punch which has deformed the metal strip 18 and the upper edge of metal plate 12. This second punch is not shown in the drawing. By supporting the tongues 19, 20 during this second punching operation by means of a support, the free edges of these tongues 55 may, as has been mentioned above, during the

same punching operation, be brought into complete contact with metal plate 12. After this second punching operation, the metal strip 18 is flattened as indicated by reference character 18a (Figure 3), and lies against and presses against the punched out edge 26 of metal plate 12, so that edge 26 is held firmly and steadily between metal strip 18a and tongues 19, 20. This fastening method is simple, cheap and effective and is possible to accomplish with simple means and with rapidity.

Figures 5, 6 and 7 show a side view, a cross section and a horizontal view, respectively, of the original position of parts for the fastening of an edge of one or more U-shaped metal plates 27 to the surface of a plane metal plate 28, which, for instance, consists of a part of a closed frame work. Figures 8 and 9 correspond to Figures 5 and 6 and show the appearance of metal plates 27 and 28 after accomplishing the first punching operation on metal plate 28, with punch 29, each U-shaped metal plate 27 serving as a die during this initial punching operation. Punch 29 has the same width and form as the inner edge of the U-shaped metal plate 27. The form of punch 29, therefore, varies in accordance with the form of the work-piece which is to be fastened to the plate 28. In the example shown, the punch 29 has a cross-sectional form or configuration corresponding to the surface 30, 31, 32, 33 in Fig. 7. The lower surface of punch 29 is arched according to Figure 9, and the side surfaces 34 and 35 of punch 29 form sharp edges (see Figure 8) with bottom surface 35 in order to cut metal plate 28, while the other side surfaces 37 and 38 of the punch 29 form rounded edges with the bottom surface 36 of the punch in order not to cut metal plate 28 (see Figure 9). By the pressing down of the punch 29 against metal plate 28, a metal strip 39 is cut and is pressed down out of metal plate 28, which metal strip with its downwardly bent part lies against the inner sides of the legs of metal plate 27, each end of said downwardly bent part being united with metal plate 28. In Figure 7, lines 30-31 and 32-33 represent cutting lines where metal plate 28 is cut through by punch 29, while metal strip 39 is united with metal plate 28 along the places 31-32 and 30-33. Each U-shaped metal plate 27 is, after this punching operation, partly held by metal plate 28. For complete fastening of the U-shaped metal plates to metal plate 28, still one or more punching operations performed with another punch, are required. These operations are evident from Figures 10 and 11, in which Figure 10 corresponds to Figure 8 after accomplishing these last punching operations, and Figure 11 is a cross-section of Figure 10 between two U-shaped metal plates 27 lying near each other.

If a plurality of U-shaped metal plates 27, arranged in a line after each other and at a distance from each other, are to be fastened to a common metal plate 28, this is effected by means of a punch with a form 40 shown in full lines in Figure 10, which punch is shown in side elevation in Figure 11. This punch 40 having an arched bottom surface, is punched downwardly against the remaining parts, designated 41 in Figure 8, of the metal plate 28, said parts being situated between the down pressed metal strips 39. By this down pressing, the parts 41 are bent to the form designated 41a in Figures 10 and 11, while simultaneously with such bending, the upper edges of the U-shaped metal plate are deformed so that they are bent in over the metal strips 39. The

last mentioned bendings are designated 42 in Figure 10. Parts 41a and 42 are bent only, or else they are both bent and stretched, depending upon the force with which the deformation is effected. By the method here described, the punch 40 at each operation thereof fastens to metal plate 28 one edge of each of two U-shaped metal plates 27 lying near each other, and as the punch 40 passes over all U-shaped metal plates, all of these are fastened at both sides. Punch 40 is also utilized for fastening the outermost legs of the outermost U-shaped metal plates, but in Figure 10 this is not shown. Instead, this figure indicates how these outermost legs may be fastened, if desired, by means of a punch with a somewhat differing shape (compare the impression 41b of this punch in Figure 10). It is evident from what is described that with this fastening method, the ends 42 of the U-shaped metal plates are brought to a secure and locking engagement between parts 41a and 39 of metal plate 28 in a simple and cheap manner.

If the object is only to fasten one U-shaped metal plate 27 to a metal plate 28, this may be effected by means of a second punch simultaneously effecting the deformations 41a and 42 at both sides of one U-shaped metal plate 27. A punch or deforming tool of this type is indicated in Figure 10, which punch includes a first punch member 40 and a second punch member 40a indicated in dash-dotted lines in said figure.

The invention here described is not restricted to the embodiments shown which are only to be considered as examples because the idea of the invention may be realized also in other ways.

Having now described my invention, what I claim as new, and desire to secure by United States Letters Patent, is:

1. In the method of fastening a work-piece having spaced wall portions at one end edge thereof to a plane plate member disposed perpendicular to the wall portions of the workpiece, the steps which comprise utilizing the work-piece as a die and severing and displacing from the plate in the direction of the work-piece an integral strip portion to engage endwise inwardly of the work-piece between the spaced wall portions thereof, and deforming simultaneously the portions of the plate laterally adjacent said strip and the underlying end edge portions of the spaced walls of the work-piece to interlock said end edge portions of the work-piece between the displaced strip and deformed portions of the plate.

2. In the method of fastening a work-piece having spaced wall portions at one end edge thereof to a plane plate member disposed perpendicular to the wall portions of the workpiece, the steps which comprise utilizing the work-piece as a die, severing from the plate an integral strip portion and simultaneously displacing the same in the direction of the work-piece to engage endwise inwardly thereof between the spaced wall portions thereof, and then deforming in the direction of the work-piece the plate portions at opposite sides of the displaced strip to cause the underlying end edges of the spaced walls of the work-piece to be turned inwardly thereof and engaged over the intermediate displaced strip portion of the plate so that the work-piece end is interlocked between the displaced strip and deformed edge portions of the plate.

3. The method of fastening a work-piece at an edge thereof to a plane plate member disposed substantially perpendicular to said work-piece,

which comprises the steps of placing an edge of the work-piece into contact with a surface of the plate member with the plate member extending beyond at least one end of said edge, utilizing said edge as a supporting die, severing from the plate member an integral strip corresponding substantially to the width and contour of said edge by forming spaced cuts in the plate member adjacent opposite sides of said edge and within the area of said plate member and displacing simultaneously with said severing and in the direction of said work-piece integral tongue portions disposed at opposite sides of said work-piece, deforming simultaneously the said integral strip and upsetting said edge, and deforming said tongue portions toward said workpiece to bring the free edges thereof into contacting relation with opposite sides of said work-piece inwardly thereof from said edge and beneath said upset

edge, whereby to interlock said upset edge between said deformed integral strip and said tongue portions of said plate member.
